(57) **CLAIM**

The ornamental design for a clamshell container, as shown and described.

DESCRIPTION

FIG. 1 is a perspective view of a first embodiment of a clamshell container;

FIG. 2 is a front elevation view of the first embodiment of the clamshell container of FIG. 1;

FIG. 3 is a rear elevation view of the first embodiment of the clamshell container of FIG. 1;

FIG. 4 is a right side elevation view of the first embodiment of the clamshell container of FIG. 1, the left side being a mirror image thereof;

FIG. 5 is a top plan view of the first embodiment of the clamshell container of FIG. 1;

FIG. 6 is a bottom plan view of the first embodiment of the clamshell container of FIG. 1;

FIG. 7 is a perspective view of a second embodiment of a clamshell container;

FIG. 8 is a front elevation view of the second embodiment of the clamshell container of FIG. 7;

FIG. 9 is a rear elevation view of the second embodiment of the clamshell container of FIG. 7;

FIG. 10 is a right side elevation view of the second embodiment of the clamshell container of FIG. 7, the left side being a mirror image thereof;

FIG. 11 is a top plan view of the second embodiment of the clamshell container of FIG. 7; and,

FIG. 12 is a bottom plan view of the second embodiment of the clamshell container of FIG. 7.

The portions of the design shown in broken lines form no part of the claimed design.

1 Claim, 12 Drawing Sheets
